UNITED STATES PATENT OFFICE.

CLARENCE SKARE, OF KENYON, MINNESOTA.

AUTOMATIC WATER-PUMP.

1,292,897.

Specification of Letters Patent. Patented Jan. 28, 1919.

Application filed January 23, 1917. Serial No. 143,971.

To all whom it may concern:

Be it known that I, CLARENCE SKARE, a citizen of the United States, residing at Kenyon, in the county of Goodhue and State 5 of Minnesota, have invented new and useful Improvements in Automatic Water-Pumps, of which the following is a specification.

This invention relates to pumps for supplying water to a tank or reservoir for domestic or other use.

The main object of the invention is to provide an automatic pumping apparatus wherein power is obtained for actuating the pump from an internal combustion motor, 15 in connection with means controlled by the water level in the reservoir for automatically starting and stopping the motor when the water respectively falls below and reaches the predetermined level.

20 A further object of the invention is to provide a pumping apparatus embodying novel means for starting and stopping the motor, throwing an ignition circuit into and out of action, supplying gasoline or other 25 fuel for use and automatically oiling the working parts of the apparatus.

With these and other objects in view, the invention consists of the features of construction, combination and arrangement of 30 parts hereinafter fully described and claimed, reference being had to the accompanying drawings in which—

Figure 1 is a side elevation of a pumping apparatus embodying my invention with 35 parts appearing in section.

Fig. 2 is a top plan view of the same.

Fig. 3 is a view on an enlarged scale, with parts in section, showing the starter in working position.

40 Fig. 4 is an enlarged sectional view of the float and governor controlled means for controlling the supply of air to the starter.

Fig. 5 is a view of the governor and immediate connections controlled thereby.

45 Fig. 6 is a view of the air pump and controlling connections with parts in section and with the parts as they appear in non-working position.

Fig. 7 is a similar view of the air pump 50 with parts as they appear in working condition.

Referring to the drawings, 1 designates a water pump, having its inlet connected with a suction pipe 2 leading from a suitable 55 source of water supply and having its outlet in communication with a discharge

pipe 3 leading to a water receiving tank or reservoir 4. This water pump is suitably connected with and driven from the crank shaft 5 of an internal combustion engine 6 60 the fly wheel 7 of which engine is provided with gear teeth 8, for a purpose hereinafter described.

On the shaft 5 is a beveled gear 7' meshing with a beveled gear 8' on a shaft 9, which 65 shaft 9 is provided with a beveled gear 10 meshing with a beveled gear 11 mounted on a shaft 12. This shaft 12 is provided with cranks 13 and 14, the crank 13 being coupled by a connecting rod to the piston of an oil 70 supply pump 15, while the crank 14 is coupled by a connecting rod to the piston of a fuel feed pump 15'. The inlet of the pump 15 is connected by a check valve pipe 16 with a lubricating oil reservoir 17, from which 75 the lubricant to supply the working parts of the engine and other parts of the machinery is supplied, the delivery outlet of the oil pump being in communication with oil conducting tubes 18 for supplying oil to the 80 bearings and other parts to be lubricated. I have not deemed it necessary to show these tubes extended to the parts to be lubricated thereby, as this forms no direct part of my invention, and as the tubes would 85 tend to obscure illustration of the essential features of the apparatus. The pump 15' operates continuously in the operation of the engine 6 to raise gasoline or other fuel liquid from a supply tank 20 preferably embedded in the ground, and to deliver the fuel through a check valve pipe 90 21 to an overhead feed tank 22, from which the fuel is supplied through a conductor 23, by gravity or otherwise, to the carburetor 24 95 connected with the intake or intake manifold of the engine. The excess amount of oil supplied to the tank 22 drains back to the reservoir 20 through an overflow pipe 25, and a pipe 26 is provided for filling the 100 tank 20 whenever its replenishment is required.

The ignition circuit of the motor includes a battery box 27 inclosing a storage battery or other battery cells for furnishing an electric current for sparking purposes, and in said circuit are conductors 28 and 29 extending to the tank 4, the conductor 28 being connected to a pivoted lever 30 suitably mounted upon and insulated from the tank 105 110 and having an arm 31 in electrical connection with said conductor 28 and adapted to

engage a terminal 32 associated with the conductor 29 and thus forming a switch for opening and closing the electric circuit. The arm 31 is connected with a float 33 arranged to rise and fall with the level of the water in the tank 4, so that when the water falls below a predetermined level the switch will be closed to close the circuit for ignition purposes, while when the water reaches the predetermined level the switch will be opened to break the electric circuit and thus throw the ignition circuit out of action.

A starting mechanism is provided for automatically starting the motor 6 when the water in the tank 4 falls below the required level and for throwing the starter out of action after the engine has reached a predetermined speed, so that the engine may keep working while the starter, having performed its function, is thrown out of operation, until the water is again pumped to the desired level, when the ignition circuit will be cut out and the motor brought to a stop. This starting mechanism comprises a compressed air cylinder and piston 34 carried by a bracket 35 mounted to tilt in a vertical plane upon a fulcrum 36, the said piston being arranged to drive a starting gear 37, adapted by up and down pivotal movements of the starter to be thrown into and out of engagement with the gear teeth 8 of the engine fly wheel 7. The bracket 35 is connected with the piston member of an actuating cylinder and piston 38, where-by the starter may be raised to throw the gear 37 into mesh with the teeth 8, and held in such position by the pressure of air behind the lifting piston and until such pressure is relieved, when the starter tilts back by gravity to normal position.

Leading from a compressed air storage tank 39 is a main air supply pipe 40, from which leads a pipe 41 having a main controlling valve 42 therein and which is connected with a pipe 43 leading to the lifting cylinder 38, and from which leads a branch pipe 39 to the cylinder 34, which pipe 39 is preferably provided with a jointed section which accommodates itself to the pivotal movements of the starter. The pipe 43 is provided at its juncture with the pipe 41 with a controlling valve 44 having an actuating arm 45 connected with the stem of a spring retracted piston 46 arranged within a motor cylinder 47, connected by a pipe 48 with the pipe 41, so that when air is admitted to said cylinder 47 behind the piston the latter will be raised and actuate the arm 45 to open the valve 44, the air pressure maintaining the parts in such position until released. A controlling valve 49 is arranged at the junction of the pipes 41 and 48, and this valve is provided with a crank arm 50 coupled by a connecting rod 51 or link 51 with the switch lever 31, so that

the valve 49 will be opened and closed simultaneously with the opening and closing of the admission circuit and by the switch lever 31. The pipe 43 is provided with a vent or relief outlet 52 having a vent or relief valve 53 therein, provided with a crank arm 54 coupled by a connecting rod 55 with one arm of a bell crank lever 56 connected with the stem of the valve 42, so that when the main valve 42 is open for the supply of air to the starter cylinder 34 and starter lifter 38 the valve 53 will be closed to retain the air pressure, while when the valve 42 is closed the valve 53 will be simultaneously opened for the release of air from the cylinders 34, 38 and 47 so that the pistons in said cylinders may return to normal position. In the pipe 39 is a valve 57 provided with a crank arm 58 coupled by a connecting rod 59 to the cylinder 34, so that in the rising and falling movements of the generator the valve 57 will be simultaneously and alternately opened and closed. The starter piston working in the cylinder 34 may be spring actuated, or any suitable type of slide valve mechanism may be provided for admitting air to positively operate the piston in its back and forth motions. It will thus be understood that when the water in the tank 4 falls below the predetermined level the ignition circuits which will be closed and the valve 49, which is normally closed, will be opened to allow air to pass through the normally opened valve 42 to the cylinder 47 whereby the valve 44 will be opened to supply air to the generator lifter which will be raised to operative position, the upward movement of the generator at the same time opening the valve 57 to supply air to the starter cylinder, whereby the starter will be thrown into action to start the engine the parts being maintained in this position until the engine reaches a speed greater than that of the normal speed of the starter gear 37, at which time an automatic governor mechanism will be thrown into operation to throw the starter out of action while permitting the engine to continue working. When the starter is thrown out of action the valve 57 will be automatically closed, and the valve 42 will be simultaneously closed by the governor mechanism, thus cutting off the supply of air to the starter cylinders and opening the valve 53 for the vent of the air to the atmosphere, the piston 46 on returning to normal position simultaneously closing the valve 44. The valve 49 will, however, remain open, without influence, as long as the float 33 remains below the predetermined level of the water in the tank 4, so that the ignition circuit and motor will remain in action to pump water into the tank 4 until the normal level of the water therein is reached, at which time the igni-

tion circuit will be thrown out of action and the motion of the engine and the water pump arrested, as previously explained.

The governor mechanism referred to comprises a centrifugal type of governor 60 having its weighted governor arm 61 connected as usual with a grooved sliding collar 62, for raising and lowering said collar on the governor staff in the inward and outward movement of the governor balls. The shaft of this governor is driven by a suitable gearing 63 from the shaft of the engine 6, and the grooved collar 62 is operatively connected with bell crank lever 64 which is coupled by a rod 65 to the other arm of the bell crank lever 56, whereby when the speed of the engine reaches a certain degree the outward movement of the governor balls in drawing the grooved collar upward will communicate motion through the connection 65 to close the normally open valve 42 and thus throw the starter out of action, the valve 42 remaining closed as long as the engine is in action and until it is stopped, whereupon the grooved collar in its descent will reopen and reset the valve 42 in normally open position for action as hereinbefore described.

Thus it will be understood that the governor mechanism will automatically effect the cut-off of the supply of air to the cylinders associated with the starter, whereby the starter will be caused to return to normal position and its gear actuating cylinder 35 and piston simultaneously thrown out of operation.

In practice, the air reservoir 39 is initially primed or charged with air compressed to a desired density, and provision is made for replenishing this reservoir with air when the pressure therein falls below that intended to be constantly maintained. The device for keeping the air tank charged with air comprises an air supply pump 66 the cylinder of which is provided with a check valve intake 67 and a check valve outlet 68, the latter being connected with the main air supply pipe 40 by a feed pipe 70. The pump plunger or piston 71 has its rod or stem 72 connected with a reciprocating head 73 movable in cross head guides 74 in which also moves a cross head 75 coupled by a connecting rod 76 with a pump driving gear 77 driven from a gear 78 on the motor shaft. The pump plunger is adapted to be operated on its backward stroke by an actuating spring 79 connected with the head 73, and to be impelled on its forward stroke by the cross head 75. The pump plunger is normally held inactive and at the limit of its forward or discharge stroke by a latch device consisting of a latch member 80 on the rod or stem 72 which is engaged by a latch member 81 on the longer arm of a lever 82. The said long arm of the lever 82 is adapted

to be retracted by the action of a spring 83 and is limited in its retracting movement by a stop 84 on the guide 74. When the latch member 81 is retracted the piston is free to be drawn backward by a spring 79 and to be forced forward on its compression and discharge stroke by the cross head 75. The short arm of the lever 82 is connected with a piston in a controlling cylinder 84, which is connected at its upper end by a pipe 85 with a branch pipe 86 leading from the pipe 70, whereby the piston in said cylinder 84 is normally subjected to the pressure in the air feed line and is forced downward in said cylinder thus holding the latch member 81 in engagement with the latch member 80 to maintain the pump in an inoperative condition as will be readily understood.

A relief pipe 87 is connected with the upper end of the cylinder 84 and has arranged therein a valve 88 the stem of which is provided with a crank arm 89 coupled by a connecting rod 90 with a plunger 91 in the pipe 86, said plunger being normally held depressed to hold the valve 88 closed, thus maintaining the pressure in the cylinder 84 to hold the latch member 81 projected. In the pipe 85 is a controlling valve 91 which is connected with a lever 92 controlled by an actuating spring 93 and pivoted to the connecting rod 90, the construction being such that the valve 91 is normally held in open position when the plunger 90 is depressed against the resistance of the spring 93, which is thereby held in a tensioned condition. When, however, the pressure in the air tank 39 and the air feed line falls below a predetermined degree, the spring 93 overcomes the pressure against the plunger 90 and raises said plunger thereby closing the valve 91 against the supply of air to the cylinder 84 and opening the valve 88 to permit the air contained in the top of said cylinder to exhaust, thus allowing the spring 83 to draw the long arm of the lever 82 downward and throw the latch member 81 out of engagement with the latch member 80, whereupon the spring 79 will be free to move the pump plunger on its suction stroke and said spring and the cross head 75 will reciprocate the head 73 of the pump plunger back and forth, whereby the air in the tank and air line will be replenished and restored to normal working pressure. As soon as this occurs the plunger 90 will again be forced downward, thus closing the valve 88 and opening the valve 91 to again supply air to the cylinder 84, thus resetting the latch member 81 to engage and hold the pump plunger from backward movement, whereby the pump will be thrown out of operation. The operation above described whereby the air pump is thrown into and out of action will be repeated in the running of the driving motor whenever the pressure in the tank falls be-

low the predetermined degree, thus keeping the air pressure at the proper stage for supplying air to operate the starter.

From the foregoing description taken in connection with the accompanying drawings, the construction and mode of operation of my improved water pump will be readily understood, and it will be seen that the invention provides a pump operated by an internal combustion motor combined with means, controlled by the level of the water in the receiving tank, to throw the motor into and out of operation whenever a replenishment of the tank with water up to a prescribed level is required, the construction being such that the apparatus requires little or no attention, care being only necessary to keep the parts in proper working condition. While the construction and arrangement of parts disclosed is preferred, it will, of course, be understood that changes in the form, proportion and arrangement of parts within the scope of the appended claims may be made without departing from the spirit or sacrificing any of the advantages of the invention.

I claim:

1. In a water pumping apparatus, the combination of a water receiver, a water pump, an internal combustion motor for driving the pump, a starter for starting the motor, ignition means for the motor, a pivotally mounted frame and fluid pressure means connected therewith for rendering the starter operative and inoperative, means controlled by the speed of the motor for governing said fluid pressure means for rendering said starter inoperative, and float controlled means governed by the level of the water in the receiver for controlling said ignition means and fluid pressure means to start the motor.

2. In a water pumping apparatus, the combination of a water receiver, a pump, an internal combustion motor for driving the pump, ignition means, a fluid pressure controlled starter for starting the motor and including a source of fluid pressure supply, means controlled by the speed of the motor for governing the fluid pressure means to throw the starter out of action, means governed by the level of the water in the receiver for controlling the ignition means and also for controlling the fluid pressure, means to throw the starter into action, a pivoted frame for mounting said fluid pressure controlled starter, and fluid pressure means for throwing the frame into position to render the starter operative.

3. In a water pumping apparatus, the combination of a water receiver, a pump, an internal combustion motor for driving the pump, ignition means, a starter adapted to

be thrown into and out of gear with the motor and normally out of gear therewith, fluid pressure means for throwing the starter into gear with the motor and operating the same, means controlling said fluid pressure means and governed by the speed of the motor for throwing the starter out of action, said starter including a motor, a wheel driven thereby and a frame pivotally mounting the motor and wheel, and means controlled by the level of the water in the receiver for governing the ignition means and also controlling the fluid pressure means for throwing the starter into action.

4. In a water pumping apparatus, the combination of a water receiver, a pump, an internal combustion motor for driving the pump, ignition means, and a governor driven from the motor, a starter movable into and out of gear with the motor and normally out of gear therewith, fluid pressure means for controlling the starter and operating the same, a float in the receiver for controlling the ignition means and also controlling the fluid pressure means for throwing the starter into action, and means controlled by the governor for controlling said fluid pressure means to throw the starter out of action when the speed of the engine reaches a predetermined point, said means controlled by the governor including a pressure cylinder and a piston therein, an inlet pipe for the cylinder, a valve in the inlet, means controlled by the float for operating the valve, a valve controlled by the plunger for admitting pressure to the means throwing in the starter, an inlet valve controlled by the engine governor and a valve simultaneously and reversely operated by the governor for relieving pressure on the plunger.

5. In a water pumping apparatus, the combination of a water receiver, a pump, an internal combustion motor for driving the pump, means governed by the level of the water in the receiver for throwing the motor into and out of action, a fuel reservoir, a fuel receptacle above the level of the fuel reservoir, a pump actuated by the motor for constantly raising fuel from the reservoir to the receptacle, and an overflow connection for returning the excess amount of fuel from the receptacle to the reservoir, and pressure controlled means comprising a plurality of plungers and cylinders, and a plurality of valves one of which is opened when the other is thrown to closed position by a given movement of one of the plungers, for rendering inactive one element of the pump last named by reason of the movement of the other plunger.

In testimony whereof I affix my signature.

CLARENCE SKARE.
